CLAIM

The ornamental design for an electronic device, as shown and described.

DESCRIPTION

FIG. 1 is a top, front, right-side perspective view of an electronic device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof; and

FIG. 9 is another top view thereof.

The crosshatched pattern shown represents a woven fabric, and is understood to be distributed uniformly over the surface of the claimed design upon which the pattern occurs. The dashed broken lines depict portions of the electronic device that form no part of the claimed design.
